United States Patent Office.

LORIN C. SPRINGER, OF CHICAGO, ILLINOIS.

Letters Patent No. 60,953, dated January 1, 1867.

IMPROVEMENT IN MAGNETIC LOCKS.

The Schedule referred to in these Letters Patent and making part of the same.

TO ALL WHOM IT MAY CONCERN:

Be it known that I, LORIN C. SPRINGER, of Chicago, in the county of Cook, and State of Illinois, have invented a new and useful Electro-Magnetic Safe Lock; and I do hereby declare and make known that the following is a full, clear, and exact description of the same, reference being had to the accompanying drawings, and the letters and figures marked thereon, which form part of this specification.

My invention consists in unlocking or withdrawing the bolts which secure the door of a safe, by opening and closing an electro-magnetic circuit, and also by passing the circuit by which said result is accomplished through a series of movable contiguous points, so that by displacing said points, or any one of them, the aforesaid circuit is broken. My invention further consists in controlling and moving the said movable points in the aforesaid circuit, by opening and closing a series of electro-magnetic circuits arranged in connection therewith, respectively, so that one familiar with the lock can readily adjust said points to complete the first-mentioned circuit, so that the bolts may be withdrawn; while one not familiar with the lock cannot, by any probability, connect said circuit, and therefore cannot open the safe.

To enable those skilled in the art to understand how to construct and use my invention, I will proceed to describe the same with particularity, making reference in so doing to the aforesaid drawings, in which—

Figure 1 represents a front elevation of a safe having my said invention attached.

Figure 2, an interior elevation of the safe door, showing a plan view of my invention; and

Figure 3 is a plan or top view of the door, slightly ajar, disclosing the mode whereby the bolts of the lock adjust themselves when the door is closed.

Similar letters of reference in the several figures indicate the same parts of my invention.

A represents the door of the safe hinged, as shown, to the safe in the usual manner. R R represent two bolts, which are connected by a spring, S, which draw said bolts back from their beds in or upon the safe, and unlock the safe whenever the block P is withdrawn from between the adjacent ends of said bars, as hereinafter described. To lock the safe, the block P is adjusted, as shown, between the bolts R, and the door closed; the outer ends of the bolts strike against the catches m, which yield to the pressure until the bolts pass far enough back to allow the springs o to throw said catches, which are arranged at the top and bottom alike behind said bolts, and thus secure the door. Any other suitable means may be employed to receive the ends of the bolts, instead of the one above described. E E represent an ordinary spool magnet, upon or over which is arranged a lever, F, provided with an armature, F', arranged substantially as in telegraphic instruments. To the opposite end of the lever F is attached a hook or catch, marked M, which operates upon the toothed wheel J, as shown in fig. 3; N representing a pawl to prevent the said wheel J from moving back when the hook M is released, as hereinafter set forth. B C D represent a series of similar magnet spools, having a corresponding series of levers, L, each operating upon a corresponding series of toothed wheels, G H I, in the same manner that the lever F operated upon the wheel J, as aforesaid. O represents an arm, attached at one end to a suitable crank device upon said wheel J, and the other end to a block, P, which holds the bolts R in the sockets or catches which secure the door of the safe, as aforesaid. The end of said arm O is suspended from a swinging hauger, Q, to hold it in place when withdrawn from between the said bolts, as hereinafter set forth. The wires passing around the magnet B pass out through the door of the safe, at the small apertures b' b', or, rather, terminate in said apertures, being properly insulated, so that a circuit is completed around said magnet B, by bringing the opposite poles of a battery, T, in contact therewith, as shown in fig. 1. The wires passing around the magnets C D E, marked, respectively, o d o, are similarly arranged with respect to the small apertures o' d' o', as shown, so that circuits may be completed around the magnets by connecting the opposite poles of said battery therewith, as aforesaid. It will be observed that a portion of the circuit a, through or around the magnet E, passes through arms, e f g h, attached, as shown, to the wheels G H I, said part of the circuit being properly insulated from said wheels and their supports and shafts, so that when arranged in contact with points upon the adjacent wheels, the circuit is complete; but when one or more of said wheels are moved from such position, the circuit a is broken at said points, or some of them.

When the safe is to be locked, one or more of said wheels, G H I, is moved a certain distance, so as to break the said circuit a, when the door is closed and is locked automatically. By observing how far each or either

of said wheels is turned from the position in which said circuit α is completed, one may readily know how to readjust the same in said position, when desired to unlock the safe. This readjustment is effected by applying the poles of the battery to the ends of the wires passing around the magnet which corresponds with the wheel to be moved, which completes said circuit, and the magnet draws down the corresponding lever L, and raises the opposite end of said lever, the hook M revolving the wheel one notch. By removing one or both poles of the battery, the circuit is broken, the magnetic attraction ceases, and the lever is thrown to its former position by means of a spring which releases the hook M, the pawl N, however, holding the wheel in position. By completing said circuit again, the wheel is revolved another notch or space, and, by repeating the closing and opening of said circuit, the wheel is readjusted in the proper position, as required. If more than one wheel had been displaced, a similar operation upon the corresponding magnet will readjust it, and thus the circuit α be made complete, so that by applying the poles of the battery, as aforesaid, the lever F operates upon the wheel J in the manner above described. This revolution of the wheel J gradually withdraws the block P from its position between the bolts R, and when said block is wholly withdrawn, the spring S withdraws the said bolts and unlocks the safe. If desired, the wires of the several circuits may all be brought outside of the safe, through a single orifice; or, the various orifices may be made in different parts of the door, instead of being arranged symmetrically, as shown. A series of any number of wheels, G H I, may be employed, the greater number rendering the probabilities of accidental adjustment of the circuit α proportionally less, and the number of teeth upon each wheel also decreasing such probabilities; and the two features combined rendering such readjustment infinitely improbable.

Having described the nature and operation of my invention, I will now specify what I claim, and desire to secure by Letters Patent:

1. I claim unlocking a safe, or withdrawing the bolts thereof, by closing and opening an electro-magnetic circuit, passing through a series of movable or adjustable points, substantially as and for the purposes set forth.
2. I claim operating upon and adjusting the said movable points in said electro-magnetic circuit, by means of a corresponding series of auxiliary circuits, substantially as described.

L. C. SPRINGER.
